SLIP SHEETER, PARTICULARLY ADAPTED FOR MIMEOGRAPHS

Filed Feb. 18, 1928

INVENTOR
Frederick Klein

UNITED STATES PATENT OFFICE

FREDERICK KLEIN, OF NEW YORK, N. Y., ASSIGNOR TO A. B. DICK COMPANY, A CORPORATION OF ILLINOIS

SLIP SHEETER, PARTICULARLY ADAPTED FOR MIMEOGRAPHS

Application filed February 18, 1928. Serial No. 255,445.

The invention relates to an improvement in slip-sheets or interleaving devices adapted for attachment to a duplicating machine, such as a mimeograph, for the purpose of interleaving the printed sheets delivered by the duplicating machine with blotters or separators to prevent the smudging of the ink on the freshly printed sheets.

The general object of the present invention is to produce a simple and efficient slip-sheeter or interleaving device of this character which will positively and accurately interleave the printed sheets with separators regardless of the speed at which the duplicating machine is operated. A more particular object of the invention is to arrange the parts of the interleaving device so that it may be rendered inoperative, and then thrown into operation again, without disturbing its synchronism with the operation of the duplicating machine. Another object of the invention is to so arrange the parts of the interleaving device that it can be made to place a separator upon a freshly printed and delivered sheet at any predetermined time with respect to the delivery of the next printed sheet. Thus by allowing an appreciable interval after the delivery of the printed sheet before the separator is placed thereon the operator is enabled to inspect the freshly delivered sheet to ascertain whether the printing has been properly done. Other and further objects of the invention will appear as the description proceeds. With these objects in view the invention consists in the improved slip-sheeter or interleaving device fully described hereinafter and particularly pointed out in the appended claims.

In the accompanying drawings illustrating the preferred form of the invention, Fig. 1 is a side elevation of the improved slip-sheeter or interleaving device showing its attachment to the delivery end of a duplicating machine; Fig. 2 is a front elevation of the operating parts of the interleaving device shown in Fig. 1; and Figs. 3, 4, 5 and 6 are detail views in side elevation of the separator delivering device and the adjacent part of the separator magazine and showing progressively a complete cycle of the delivering de-

vice in removing a separator from the magazine and delivering it.

The improved slip-sheeter or interleaving device is adapted for ready attachment to and detachment from a duplicating machine, such as a mimeograph, by means of a pair of parallel, horizontally arranged bars 1 hook-shaped at their forward ends 2 for engagement with the tie bar *a* of a mimeograph A. The bosses 3 on the bars 1 are adapted to rest upon a cross piece *b* of the mimeograph. The bars 1 are connected by the transverse bars 4 which support the guides 5 held thereon by the bolts and wing nuts 6.

The operating parts of the improved interleaving device are supported from a frame comprising the upright bars 8 inturned at their lower ends and supported on a rod 9 mounted in the upturned rear ends of the bars 1. The horizontal bars 1 and the upright bars 8 are held in operative relation with each other by means of the brace 10, the upper end of which is mounted on a rod 11 passing through the lower ends of the bars 8 and the lower end of which is secured to one of the bars 1 by means of the screw 39. By removing the screw 39 the bars 1 and 8 and the parts carried by them may be folded together about the point 9.

On the pivot or cross rod 13 fixed in the upper ends of the vertical bars 8 is mounted a pivot member 12 supporting on its forward end the upper end of a magazine for the separators or slip-sheets. The normal position of the magazine is indicated in Fig. 1 and comprises a rear wall 19, a bottom 38 secured to the lower end of the rear wall 19 for supporting the separators by their lower edges, and two side walls 14 extending forwardly from the rear wall 19. On the rear end of the pivot member 12 are pivotally mounted two upright arms comprising the lever 15. Extending forward from the upper ends of the lever arms 15 is a wire 18 formed like a hairpin. The wire 18 is normally held against the upper end of the rear wall 19 of the magazine by means of a torsion spring 17 connected at one end with the pin 20 inserted in the pivot piece 12 and at its other end with the pivot pin of a roll 16 mounted

between the arms of the lever 15. The lower end of the magazine is yieldingly pressed forward (to hold the supply of separators in position to be engaged and delivered) by means of the two springs 21 connected at their upper ends with the pin 20 and at their lower ends with the pins 22 projecting rearwardly from a cross bar connecting the two upright bars 8. When it is desired to hold the supply of separators in the magazine out of range of the separator delivering device the lever 15 is turned in a clockwise direction, viewing Fig. 1, until the roll 16 is received within the recess 25 of a bracket 24 extending rearwardly from the cross piece 23 supported from the bars 8.

The separator delivering device comprises a cylindrical gripping member or feeder tip 36 (preferably of rubber) mounted in the bifurcated outer end of a feed arm 35 the split hub of which is adjustably fixed upon a shaft 27 journaled at one end in the upper end of the upright arm part 26 of a bracket supported on extensions of the rods 9 and 11. At its other end the shaft 27 is journaled in the upper end of the arm 31 of a bracket supported on the rods 9 and 11. The shaft 27 is driven from the duplicating machine by means of a chain 30 which passes over a sprocket wheel 29 fixed on the outer end of the shaft 27. The hub of the sprocket 29 and the collar 28 by embracing the upper end of the arm 26 on opposite sides hold the shaft 27 against axial movement.

The arm 31 is provided with a rearwardly extending hook-shaped part 32 and the arm 34 of a bracket supported on the rods 9 and 11 is provided with a similar part. These two hook-shaped parts are located relatively close to and on opposite sides of the separator delivering device and constitute stops. During the normal operation of the slip-sheeter or interleaving device the springs 21 press the lower end of the magazine forwardly and hold the separators thereon yieldingly against the rear ends of the stops 32. The hub portions 33 of the brackets of the arms 31 and 34 are formed as clamps engaging the rod 11 so that the hook-shaped stops 32 may be adjusted laterally with respect to the separator delivering device.

To load the magazine with a fresh supply of separators or to render the interleaving device inoperative for any reason, the lever 15, of which the wire 18 is a convenient handle, is turned until the roll 16 is received in the depression 25 of the bracket 24. The springs 21 are strong enough to hold the roll 16 in the depression 25 and prevent the torsion spring 17 returning the lever 15 in the reverse direction. The distance between the pivot point of the roll 16 and the pivot point of the lever 15 is such that when the roll 16 is in the depression 25 the rear wall 19 of the magazine is held substantially parallel with

the upright bars 8. In this position of the magazine the separators are out of range of the gripping member 36. When the interleaving devices are to be put into operation again the operator returns the lever 15 to normal position with the wire 18 resting against the upper end of the rear wall 19 of the magazine.

The separator delivering device operates to remove a separator from the magazine and deliver it downwardly upon the pile of printed sheets supported between the guides 5 while the shaft 27 is passing through one complete rotation. The sweep or circular path described by the gripping member 36 extends outwardly beyond the hook-shaped stops 32. Consequently when the gripping member 36 encounters the outermost separator held against the rear ends of the stops 32 it pushes the bottom end of the magazine and the separators carried thereby rearwardly, as indicated in Fig. 1. As the gripping member moves upwardly it will tend to lift the whole supply of separators, but will succeed in lifting only the outermost one with which it is in contact. When the gripping member passes beyond the hook-shaped upper sides of the stops 32 and inwardly thereof the springs 21 return the stack of separators into contact with the rear ends of the stops. The gripping member lifts the outermost separator upwardly against the wire 18, the spring 17 yielding slightly. Consequently when the rotation of the shaft 27 disengages the gripping member from the separator the wire 18 under the action of the spring 17 will force the separator downwardly until the lower end thereof rests upon the recesses in the upper surfaces of the hook-shaped stops 32, as indicated in Fig. 5. The separator remains in this position until the gripping member on its next rotation encounters its lower edge. In this connection it will be noted that the upper side of the gripping member is flattened at an angle which enables it to pick up and remove the separator supported on the stops 32, as indicated in Fig. 3. As the shaft 27 continues its rotation the lower end of the separator which has just been picked up from the stops 32 by the gripping member 36 slides along the flattened part of the arm 35, aided therein by the action of the spring 17, until the lower forward edge of the separator encounters and is held by a retaining member 37 secured to the arm 35 and forming an acute angle with the flattened part thereof. As the shaft 27 continues its rotation the gripping member 36 engages with the rear side of the lower end of the separator, as clearly indicated in Fig. 4, and since the lower edge of the separator rests upon the retaining member 37 the upper end of the separator is swung forwardly and downwardly upon the pile of printed sheets.

retained between the guides 5. The separator is stripped or disengaged from the delivering device when the edge thereof held against the retaining member 37 is brought 5 into contact with the forward edges of the bracket arms 31 and 34, as indicated in Fig. 6.

While the feed arm 35 and gripping member 36 were performing their second rotation to secure and deliver the first separator 10 resting upon the hook-shaped stops 32 the gripping member 36 engaged the next separator, lifted it and permitted it to fall upon the stops 32. The separator delivering device now continues to operate in this manner until all the separators have been delivered, each separator being first lifted and deposited upon the hook-shaped stops 32 and then on the next succeeding rotation of the arm 35 removed from the stops 32 and delivered to the pile of printed sheets. 20

It will be understood that by loosening the hub part of the feed arm 35 and turning it about the shaft 27 and then securing it in an adjusted position, the separator delivering 25 device may be caused to deposit a separator upon a freshly delivered printed sheet at any time preceding the delivery of the next succeeding printed sheet. By supporting the separators in a substantially vertical position, gripping them at their lower ends and then positively forcing them downwardly onto the pile of printed sheets in timed relation with the delivery of the printed sheets, the separators are interleaved between the 30 printed sheets accurately irrespective of the speed at which the duplicating machine is delivering the printed sheets. The stiffness of the separators which are usually composed of straw or cardboard facilitates this 35 mode of operation.

The slip-sheets or separators may be of any preferred size and shape to facilitate their easy removal from the stack of printed sheets. The separators may conveniently be 40 substantially longer and narrower than the printed sheets, so that by holding the separators by the ends and the printed sheets by the sides the two may be readily separated.

Having thus described the invention what I claim as new is:—

1. A device for inserting separators between successively delivered sheets comprising, means for holding a stack of separators in upright position resting on one edge, a stop, means for yieldingly holding the lower part of the stack of separators against the stop, means for engaging, lifting and then releasing the outermost separator, said lifted separator descending onto and being supported by the stop and said lifting means then re-engaging the separator to deposit it upon the delivered sheets.

2. A device for inserting separators between successively delivered sheets comprising, means for holding a stack of separators

in upright position resting on one edge, a stop, means for yieldingly holding the stack of separators against the stop, means for engaging the outermost separator to lift it as it pushes the stack outwardly from the stop, 50 said lifting means then releasing the separator to permit it to rest on the stop, and said lifting means again engaging the separator to deposit it upon the delivered sheets.

3. A device for inserting separators between successively delivered sheets comprising, means for holding a stack of separators in upright position resting on one edge, a stop, means for yieldingly holding the stack of separators against the stop, a rotating feed arm for engaging and lifting the outermost separator and then releasing it, said lifted and released separator being supported on the stop, and said feed arm on its next rotation 55 engaging the separator to deposit it upon the delivered sheets.

4. A device for inserting separators between successively delivered sheets comprising, a magazine pivoted at its upper end for holding a stack of separators supported at 60 their lower edge, a stop, means for yieldingly forcing the lower end of the magazine toward the stop to hold the stack of separators in contact therewith, and a rotating feed arm, said feed arm on one rotation acting to engage 65 the outermost separator and lift it and then release it to permit it to be supported by the stop and on its next rotation acting to re-engage the separator and deposit it upon the delivered sheets.

5. In a device for inserting separators between successively delivered sheets, means for supporting a stack of separators on one edge, and rotating means for engaging the outermost separator by its lower end and placing 70 it on the delivered sheets, said rotating means being arranged to support the separator and impart a rotative movement thereto as it is placed on the delivered sheets.

6. A device for inserting separators between successively delivered sheets comprising, means for holding a stack of separators in upright position supported on one edge, means for engaging the front side of the outermost separator to lift it, and means for holding the lifted separator, said lifting means then acting to engage the separator on its rear side and deposit it upon the delivered sheets.

7. A device for inserting separators between successively delivered sheets comprising, a magazine pivoted at its upper end for holding a stack of separators supported at 120 their lower edge, a stop, means for yieldingly forcing the lower end of the magazine toward the stop to hold the outermost separator in contact therewith, a rotating feed arm for engaging and lifting the outermost separator and then releasing it, and means for forcing 125 the lifted separator onto the stop, said feed 130

arm on its next rotation acting to remove the separator from the stop and deposit it upon the delivered sheets.

8. A device for inserting separators between successively delivered sheets comprising, a magazine pivoted at its upper end for holding a stack of separators supported at their lower edge, a pair of hook-shaped stops, means for yieldingly forcing the lower end of the magazine toward the rear ends of the stops to hold the lower end of the outermost separator in contact therewith, a rotating feed arm operating between the stops, said feed arm acting to lift the outermost separator on one rotation, means for forcing the lifted separator onto the stops, and said feed arm acting on its next rotation to remove the separator from the stops and deposit it upon the delivered sheets.

20 9. A device for inserting separators between successively delivered sheets comprising, a magazine pivoted at its upper ends for holding a stack of separators supported at their lower edge, a stop, means for yieldingly forcing the lower end of the magazine toward the stop, a constantly operating separator delivering means for engaging the outermost separator and depositing it upon the delivered sheets, and means for holding the stack of separators out of the range of the separator delivering means.

30 10. A device for inserting separators between successively delivered sheets comprising, an upright frame, a magazine pivoted at the upper end of the frame for holding a stack of separators supported at their lower edge, a pair of stops, means for yieldingly forcing the lower end of the magazine toward the stops to hold the outermost separator in contact with the stops, a rotating feed arm operating between the stops, said feed arm having a gripping member and a retaining member, said gripping member acting on one rotation of the feed arm to engage and lift the outermost separator, means for forcing the lifted separator downward onto the stops, said retaining member cooperating with the gripping member to engage the separator on the next rotation of the arm to remove the separator from the stops and deposit it upon the delivered sheets, and means for swinging the magazine rearwardly to hold the separators out of range of the gripping member.
